UNITED STATES PATENT OFFICE.

HENRY FAWCETT, OF KIDDERMINSTER, ENGLAND, ASSIGNOR TO
J. & J. DOBSON, OF PHILADELPHIA, PENNSYLVANIA.

DESIGN FOR A CARPET.

SPECIFICATION forming part of Design No. 17,869, dated November 8, 1887.

Application filed September 28, 1887. Serial No. 250,977. Term of patent 7 years.

To all whom it may concern:

Be it known that I, HENRY FAWCETT, a subject of the Queen of Great Britain, residing at Kidderminster, England, have invented and produced a certain new and original Design for Carpets, of which the following is a full, clear, and exact description, reference being had to the accompanying drawing, forming a part of this specification.

My design is applicable more particularly to loop and cut pile carpets and to those woven with a border.

It consists, as illustrated in the drawing, of a center or body proper, composed of a solid or nearly solid ground with a representation thereon of a crown and wreath inclosing British emblems, and next it a grouping of the emblems of the various colonies and British dependencies, and small floral figures to fill up the intervening spaces. The border proper consists of three parallel rows of figures, the outer one having the crown device and the

inner ones national emblems. A corner-piece of like character, but separated from the border and center, is a distinctive feature of the design as a whole.

I claim—

1. The design for the center or body of the carpet, substantially as shown and described.
2. The design for the border proper of the carpet, substantially as shown and described.
3. The design for the corner pieces or ends of the border of the carpet, substantially as shown and described.
4. The design for the center, border, and corner pieces of the carpet as a whole, substantially as shown and described.

In testimony whereof I have hereunto affixed my signature this 24th day of May, A. D. 1887.

HENRY FAWCETT.
